(57) **CLAIM**

Applicant claims the ornamental design for the small ceiling speaker sound diffuser, as shown and described.

DESCRIPTION

FIG. 1 is a bottom perspective view of applicant's ornamental design of a small ceiling speaker sound diffuser. The

broken line showing the speaker assembly is for the purpose of illustrating the environmental context of the small ceiling speaker sound diffuser and forms no part of the claimed design.

FIG. 2 is a bottom perspective view of applicant's ornamental design of a small ceiling speaker sound diffuser. The broken line showing the diffuser barrel is for the purpose of illustrating the environmental context of the small ceiling speaker sound diffuser and forms no part of the claimed design.

FIG. 3 is a bottom plan view of applicant's ornamental design of a small ceiling speaker sound diffuser.

FIG. 4 is a front side elevation view of applicant's ornamental design of a small ceiling speaker sound diffuser. The broken line showing the diffuser barrel is for the purpose of illustrating the environmental context of the small ceiling speaker sound diffuser and forms no part of the claimed design.

FIG. 5 is a rear side elevation view of applicant's ornamental design of a small ceiling speaker sound diffuser. The broken line showing the diffuser barrel is for the purpose of illustrating the environmental context of the small ceiling speaker sound diffuser and forms no part of the claimed design; and,

FIG. 6 is a bottom perspective view of applicant's ornamental design of a small ceiling speaker sound diffuser. The broken line showing the speaker enclosure is for the purpose of illustrating the environmental context of the small ceiling speaker sound diffuser and forms no part of the claimed design.

Applicant's small ceiling speaker sound diffuser has a radially outwardly downward sloping diffuser element with demarcations thereon and grooves therein.

1 Claim, 5 Drawing Sheets
